UNITED STATES PATENT OFFICE

164,732

CHAIR

Julius Popkin, Springfield, Mass., assignor to The Berkline Corporation, Chicopee Falls, Mass., a corporation of Tennessee

Application April 14, 1950, Serial No. 9,207

Term of patent 7 years

(Cl. D15—1)

To all whom it may concern:

Be it known that I, Julius Popkin, a citizen of the United States, residing at Springfield, in the county of Hampden and Commonwealth of Massachusetts, have invented a new, original, and ornamental Design for a Chair, of which the following is a specification, reference being had to the accompanying drawings, forming part thereof:

Fig. 1 is a front perspective view of a chair showing my new design;

Fig. 2 is a rear perspective view of the chair shown in Fig. 1; and

Fig. 3 is a front elevational view of the chair shown in Fig. 1.

The characteristic features of the chair reside in the arm portions and their relation to and association with the back, seat and base as shown.

I claim:

The ornamental design for a chair, as shown and described.

JULIUS POPKIN.
